UNITED STATES PATENT OFFICE.

WALTER W. SMITH, OF SHALLOW LAKE, ONTARIO, CANADA.

BUILDING-BLOCK.

1,089,507.

Specification of Letters Patent. Patented Mar. 10, 1914.

Application filed April 29, 1913. Serial No. 784,428.

To all whom it may concern:

Be it known that I, WALTER W. SMITH, of the village of Shallow Lake, in the Province of Ontario and Dominion of Canada, have invented certain new and useful Improvements in Building-Blocks, of which the following is a specification.

This invention relates to building blocks adapted for manufacture in terra cotta, clay, cement or the like, and my object is to devise a block which is strong, which can be easily manufactured, which is readily usable in constructing walls of different thicknesses, and which will produce a wall well adapted to resist lateral pressure.

I attain my object by forming the block of L-shape in cross section and preferably hollow substantially as hereinafter more specifically described and illustrated in the accompanying drawings in which—

Figure 1 is a front elevation of my improved block. Fig. 2 a cross section and Figs. 3 to 7 end views showing my blocks as used in various types of wall.

In the drawings like letters of reference indicate corresponding parts in the different figures.

The block 1 is L-shaped in section as shown and is made of any convenient length. The arms of the L are of the same dimensions and each in width is substantially one-half the width of the block, some small allowance being made for mortar.

The block is grooved lengthwise as shown to enable the mortar used to interlock with the blocks, and thus give a wall strength to resist lateral thrusts.

As shown in Figs. 3, 4 and 5, well bonded walls of different thicknesses can be constructed of this block without using headers. So too a backing of blocks can be applied to a brick facing as shown in Fig. 6 and bonded thereto by means of headers as shown. The plastering can then be done directly on the blocks saving the furring and lathing necessary when a common brick backing is employed.

Fig. 7 shows a heavy wall where the blocks on the face of the wall are used lengthwise, while in the center of the wall the blocks 50 are laid across the wall, and where every other cross course of blocks requires to be only half the length of the adjoining courses as shown.

The blocks will usually be formed hollow 55 as shown and strengthened by means of the webs 2 which cross the internal space in alignment with the inner walls 3 of the arms of the L. The webs 2 are preferably a little more than twice the thickness of the 60 walls 3 so that, when blocks are superimposed with the webs, the webs are of substantially the same thickness as the two adjacent walls of the blocks above or below plus the mortar between. The blocks and 65 the wall thus possess ample strength to sustain crushing stresses.

What I claim as my invention is:

1. A hollow building block L-shaped in cross section and provided with an internal 70 intermediate web in each arm of the L of substantially double the thickness of the walls of the block, the arms of the L being of the same dimensions and each in width substantially half the width of the block. 75

2. A building block L-shaped in cross section, the arms of the L being of the same dimensions and each in width substantially half the width of the block.

3. A hollow building block L-shaped in 80 cross section, the arms of the L being of the same dimensions and each in width substantially half the width of the hollow block and provided with an internal intermediate 85 web in each arm of the L, said webs being each located substantially midway between the opposite outer sides of the block which it parallels.

Dated at Shallow Lake this 19th day of April, A. D. 1913.

WALTER W. SMITH.

Signed in the presence of—

B. LAWSON,
ROBERT E. YOUNG.
